UNITED STATES PATENT OFFICE.

GUSTAV DÜRR, OF DUSSELDORF, GERMANY.

STEAM-GENERATOR.

SPECIFICATION forming part of Letters Patent No. 659,217, dated October 9, 1900.

Application filed April 25, 1899. Serial No. 714,356. (No model.)

To all whom it may concern:

Be it known that I, GUSTAV DÜRR, a citizen of Germany, and a resident of Dusseldorf, Germany, have invented certain new and useful Improvements in Water-Tubes for Steam-Generators, of which the following is a specification.

This invention relates to tubular steam-generators with inclined Field tubes. Hitherto it has been customary to form near the lower or rear ends of such tubes a sudden contraction or sharp neck joining the narrow rear end with the wider main part of the said tubes, the consequence being that mud and boiler-scale was liable to settle in front of the said neck.

In order to avoid this defect, I adopt the shape represented by the accompanying drawings, in which—

Figures 1 and 2 are sections through the rear ends of boilers, showing two embodiments of the invention.

I render the transition from the wide part *a* to the narrow end *b* gradual, so as to form a conoidal extremity *c*, the lowest part or

sole of which is approximately horizontal or slightly inclined downward, so that the whole of the water contained in the tube *a*, which is set at an inclination to the boiler-wall, will flow out after the removal of the cap *d*. The 30 cap is preferably provided with an internal screw-thread, so as to form a nut adapted to be screwed onto the narrow rear end. A tight joint may be produced in any known manner.

I claim—

In a steam-generator, a Field tube set at an inclination to the boiler-wall and having a rear end which is gradually reduced, and is set in an approximately-horizontal or slightly-inclined plane to prevent stagnation within 40 the tube, combined with a cap adapted to close the narrow rear end of the tube, substantially as specified.

Signed by me, at Dusseldorf, Germany, this 4th day of April, 1899.

GUSTAV DÜRR.
